(57) **CLAIM**

I claim, the ornamental design for a parking terminal, as shown and described herein.

DESCRIPTION

FIG. 1, is a front top right perspective view of the parking terminal, showing my new design;

FIG. 2, is a front elevation view thereof;

FIG. 3, is a rear elevation view thereof;

FIG. 4, is a left side elevation view thereof, the right side being a mirror image view thereof;

FIG. 5, is a top plan view thereof;

FIG. 6, is a bottom plan view thereof; and,

FIG. 7, is a cutaway enlargement of the card insert slot illustrated in FIG. 1.

1 Claim, 6 Drawing Sheets
